UNITED STATES PATENT OFFICE.

CHARLES L. DEPOLIER, OF BROOKLYN, NEW YORK.

WATCH.

1,306,140.

Specification of Letters Patent. Patented June 10, 1919.

Application filed December 6, 1918. Serial No. 265,495.

To all whom it may concern:

Be it known that I, CHARLES L. DEPOLIER, a citizen of the United States, residing in the borough of Brooklyn of the city of

5 New York, in the State of New York, have invented certain new and useful Improvements in Watches, of which the following is a specification, reference being had to the accompanying drawing, forming a part 10 hereof.

The effect upon watches of sudden changes of temperature has long been understood. The burden of taking precautions to prevent such changes of temperature is thrown 15 upon the user. In the recent and greatly extended use of wrist watches, particularly among military men, it has been found that the deficiencies of such watches as reliable time-keepers are due in large measure to 20 the fact that by reason of the immediate contact with the flesh of the wearer they are subjected constantly to a temperature which, although not excessive, is considerably higher than the normal atmospheric tem- 25 perature. Apparently the bad effect of this constant temperature above the normal is due directly to the effect of such continued high temperature upon the lubricant, which after a considerable period of time is found 30 to have disappeared or to have been changed in quality to such an extent that the time keeping qualities of the watch are reduced. The object of this invention is to provide practical and efficient means for protecting 35 a watch, particularly a wrist watch, from the effect of long continued heating above the normal by reason of the immediate contact with the flesh of the wearer. Practical considerations of use make it impossible to 40 resort to expedients which would otherwise suggest themselves, that is to say, the watch must not be unduly thick and it must not have within the case any material which might, in the course of time, release dust to 45 enter the movement of the watch. On the other hand, the most effective heat insulating materials are for the most part of such character that they will absorb moisture or 50 grease or will wear rapidly if in contact with the flesh of the wearer. The object of this invention, therefore, is to provide effi- 55 cient means for insulating a watch, particularly a wrist watch, from the heating action to which it would otherwise be subjected by reason of contact with the wrist or body of the wearer, and shall meet the practical re-

quirements of use as above suggested. In accordance with the invention the provision for heat insulation is external to the watch-case which incloses the movement and provision is also made for the protection of the 60 heat insulation.

The invention will be more fully explained hereinafter with reference to the accompanying drawing in which it is illustrated 65 as embodied in several possible constructions, and in which—

Figure 1 is a view in rear elevation of a watch to which the invention is applied.

Figs. 2, 3, 4, 5, 6 and 7 are detail views in 70 section, on the plane indicated by the broken line 2—2 of Fig. 1, showing different embodiments of the invention.

Obviously the heat insulating means may be applied both to the front and back of 75 a watch, but for ordinary purposes, particularly in a wrist watch, it is sufficient that the insulation be applied to the back of the watch, as indicated in the several figures of the drawing. It is sufficient, therefore, to 80 represent in the drawing the back member of the watch as having the insulating means embodied therewith. In the application of the invention illustrated in Fig. 2, the back member *a* of the case is shown as recessed 85 on its rear or outer face, as at *a'*, to receive a sheet *b* of suitable insulating material, such as asbestos. The material named and found generally desirable as a heat insulating material would not wear well if subjected to friction and would absorb damp- 90 ness and grease. It is therefore necessary to protect externally the insulating means and for this purpose there is provided a cap *c* which extends nearly over the entire 95 surface of the insulating material, but is not allowed to come directly in contact with the rim *a'* of the case member, in order that the transmission of heat to the watchcase from the cap by conduction may be avoided. 100 The cap therefore is extended not quite to the rim but far enough to protect the insulating material from wear, a narrow, annular space between the watch and the cap and the rim of the case being left, as at *a''*. 105 For securing the cap in position, pins may be employed as they are commonly employed in securing a watch dial in position. The conduction of heat from the cap to the case through such pins is negligible.

If desired provision might be made for insulation by a dead air space as well as by

such insulating material as asbestos. In Fig. 3, the cap *c* has at its periphery a lip or flange *c*² which raises the cap sufficiently to form under it a dead air space. As shown in Fig. 3 both the asbestos insulation and the dead air insulation are provided for, while in Fig. 4 the asbestos insulation is in the form of an annulus *b*¹ which serves mainly to prevent direct contact, at its edge, 10 of the cap *c* with the case member *a*.

In Fig. 5, the rim *a*⁴ of the case member is shown as adapted, like the bezel of a watch-case, to receive a metal disk or plate *a*⁵ which has secured to it by pins *c*¹ the asbestos insulation *b* and the protecting cap *c*, substantially as shown in Fig. 2, the metal disk *a*⁵ being held in place in the rim by pressing the metal of the rim down upon the edge of the plate.

20 In Fig. 6, the case member *a*⁶ is shown substantially as in Fig. 2, with the insulating material applied thereto substantially as in Fig. 2 but with the protecting cap *c*² held in place, with the insulating material, by having the edge of the recess in the case member rolled down upon it as shown at *a*⁷. This arrangement, however, is less desirable because of the contact of metal to metal between the cap and the case member.

30 In Fig. 7 is illustrated an arrangement similar to that shown in Fig. 5, in which the

metal plate or disk *a*⁵ is secured in the rim *a*⁴, but in this case the insulating material *b* is carried around the edge of the protecting plate *c*³, as shown at *a*⁸ and the edge of the rim *a*⁴ is rolled down to hold the insulation and the cap in place.

Various other embodiments of the invention will suggest themselves.

I claim as my invention:

40 1. In a watch case, the combination of a case member and a protecting plate secured to the case member and heat insulation interposed between the case member and the plate.

45 2. In a watch case, the combination of a case member and a sheet of heat insulating material applied to the case member externally and a protecting plate secured to the case member external to the heat insulating material.

50 3. In a watch case, the combination of a case member and a protecting plate secured to the case member, a sheet of insulating material applied to the external face of the case member, and a protecting cap secured to the case member and having its edge resting against the sheet of insulating material and out of contact with the case member.

55 This specification signed this 5th day of December, A. D. 1918.

CHAS. L. DEPOLIER.
